MANUFACTURE OF TUBES

Carl W. Littler, Pittsburgh, Pa., assignor to Jones
& Laughlin Steel Corporation, Pittsburgh, Pa.,
a corporation of Pennsylvania

Application July 3, 1933, Serial No. 678,808

20 Claims. (Cl. 29—33)

This invention relates to the manufacture of tubes, and more particularly to the manufacture of seamless tubes having relatively thin walls. It relates still more particularly to the manufacture of small diameter tubes such as are used in boilers, stills, etc.

The invention further relates to the manufacture of tubes having relatively small diameters and relatively thin walls by performing a part of the operation on a push bench. In the push bench process of tube manufacture a heated billet is pierced in a press throughout the greater portion of its length to form a "bottle" which is then placed over the nose of a mandrel and pushed thereby through a series of aligned dies to thin and elongate the bottle over the mandrel to form a tube blank. The push bench has certain distinct advantages among which are that the operation may be performed economically at high speed and that a quality of steel may be used in a push bench which would be entirely unsatisfactory for use in the formation of tubes by the piercing process.

However, the push bench process has certain limitations as to the wall thickness, length and diameter of tubes formed thereby. Particularly with respect to wall thickness a limitation is imposed by reason of the fact that the great pressures exerted on the blank when it is pushed through the dies in the push bench place the metal under great tensile stress and tend to tear it. Therefore it is not practicable to form extremely thin walled tubing on a push bench.

It has heretofore been proposed to form a relatively short thick walled blank in a push bench and then, after stripping, to pass the same through a reducing mill to reduce the diameter and increase the length. However, as the tendency of a reducing mill is to increase, rather than reduce, the wall thickness, this method is not satisfactory for the production of thin walled tubing.

Thin walled tubing can be very satisfactorily and economically manufactured by first forming on a push bench a relatively short thick walled tube blank and thereafter elongating said blank and thinning its wall over a mandrel. The elongating and thinning operation performed subsequently to the push bench operation is preferably carried out by passing the blank having a mandrel therein through an elongator between cross rolls which simultaneously thin and elongate the blank over the mandrel and loosen the blank on the mandrel so that it may easily be stripped. This is a consideration of some conse-

quence as the problem of stripping assumes difficulty when the wall thickness of the blank is considerably reduced.

The mandrel emerging from the push bench and having thereon the blank which has been thinned and elongated in the push bench may be passed immediately through an elongator wherein the blank is further thinned and elongated over the same mandrel and at the same time loosened to facilitate stripping; or the blank may first be stripped from the push bench mandrel, preferably after having been loosened by a reeler, and may then, with or without reheating, have another mandrel introduced thereinto and the subsequent elongation performed over the second mentioned mandrel. In the latter case the second mentioned mandrel may be of materially less diameter than the push bench mandrel, this being particularly desirable when relatively small diameter tubing is to be formed. In such case the elongator spins and reduces the blank about the smaller mandrel and at the same time reduces its wall thickness. The closed end of the blank emerging from the push bench may be sawed or cropped off at any time during the operation either before or after reheating or passing the same through the elongator.

The blank emerging from the elongator has the elongator mandrel removed therefrom, this being rendered relatively easy by reason of the loosening action of the elongator, and such blank may then be passed to and through a reducing mill to further reduce the diameter of the blank and further elongate it. This additional step is highly desirable in the manufacture of tubing of extremely small size. The preceding passage of the blank through the elongator is particularly well adapted to prepare the blank for passage through the reducing mill, as the reducing mill has a tendency to slightly increase the wall thickness of the blank, whereas the elongator is particularly well adapted for reducing wall thickness, and therefore the wall thickness may be reduced in the elongator to such a point that after passage of the blank through the reducing mill, with the attendant slight increase in wall thickness, the desired ultimate wall thickness will be obtained. Furthermore, the use of the elongator enables doing away with several passes of the reducing mill, particularly if the elongator mandrel is materially smaller in size than the push bench mandrel, a single pass through the elongator being capable of accomplishing the work of several passes through the reducing mill.

More than one elongator pass may be utilized if desired, although on account of the relatively great amount of work capable of being performed in a single elongator pass one pass will be sufficient for most ordinary purposes. In the manufacture of tubing of minimum wall thickness more than one elongator pass may be desirable.

Certain particular advantages arise by reason 10 of the passage of a blank through an elongator after formation in a push bench. Sometimes the blanks formed on the push bench tend to have a somewhat uneven wall thickness, and the elongator tends to reduce any eccentricity and 15 increase the uniformity of the wall thickness. This is probably brought about by reason of the spinning action in the elongator.

Other details, objects and advantages of the invention will become apparent as the following 20 description of certain present preferred embodiments thereof proceeds.

In the accompanying drawings I have shown certain present preferred embodiments of the invention, wherein

25 Figure 1 is a diagrammatic plan view of a portion of a tube mill;

Figures 2A and 2B taken together constitute a diagrammatic plan view of a portion of a tube mill of modified design; and

30 Figure 3 is a diagrammatic plan view of a reducing mill.

Referring more particularly to Figure 1, reference numeral 2 designates generally a push bench, the particular portion of the bench being shown being simply the conveyor or runout table carrying the blank with the mandrel therein after passing through the dies. As no specific improvement in the push bench per se is herein described or claimed, the purely diagrammatic 40 representation of the push bench by its runout table will suffice for the drawings.

Reference numeral 3 designates generally an elongator which comprises cross rolls 4 suitably mounted for rotation and having their faces designed to materially thin and elongate the wall of the blank over the mandrel. The cross rolls are driven by a motor 5 through gearing 6 and driving connections 7. Guides 8 insure proper alignment of the mandrel and blank and proper 45 introduction thereof into a passage thereof through the elongator. A conveyor 9 also assists in advancing the mandrel and blank to the elongator. The mandrel and blank may be advanced either by the provision of driving means for at 50 least some of the conveyor rolls or in any other well known manner.

The elongator 3 materially thins and elongates the blank over the mandrel additionally to the thinning and elongation accomplished in the 55 push bench. Even though a relatively cheap quality of steel is used for the push bench operation, the latter seems to have the effect of consolidating and solidifying the metal at least to such an extent as to permit of relatively heavy 60 reductions in the elongator. It is possible in the elongator to increase the length of the blank to from two to five times its original length or more, the setting of the elongator being ordinarily determined by the length of the mandrel 65 and the particular product desired.

The blank and mandrel after leaving the elongator pass along a runout table 10 from which they are lifted by fingers 11 and transferred laterally on rails 12 to a roller conveyor 13 70 which moves the same to the left into coopera-

tive relationship with a stripper 14, which may be of any desired or well known construction and which pulls out the mandrel, the blank remaining in place against a stop. The blank is then lifted out of the conveyor 13 by fingers 15 and 5 passes laterally along rails 16 to another roller conveyor 17 which advances the blank to the left through guides 18 and 19 until its forward end rests upon a roller conveyor 20. The rear end of the blank is positioned to have its closed 10 extremity sawed off by the rotary saw 21. If desired the front end of the blank may also be sawed off.

The blank on the conveyor 20 after one or both of its ends have been sawed off may be considered 15 to be a finished article of commerce or tube, although it is also adapted for further treatment in a reducing mill either with or without reheating. If desired, the blank may be passed toward the left along the conveyor 20 directly into a reducing 20 mill 22 illustrated diagrammatically in Figure 3. Such mill may be of any desired or well known construction and by successive passes reduces the diameter of the blank. The reducing mill shown in Figure 3 comprises successive stands of rolls, 25 each stand comprising a pair of cooperating reducing rolls mounted to rotate about parallel axes lying in a plane perpendicular to the axis of the blank, the axes of the rolls of successive stands being alternately criss-crossed.

Figures 2A and 2B are complementary and are adapted to be fitted together along the line X—X at the left hand side of Figure 2A and the line X—X at the right hand side of Figure 2B. These figures show a modified mill construction. 35 As in Figure 1, the push bench is indicated diagrammatically at 23, being represented by its runout table, and the mandrel having the blank thereon passes directly to a reeler 24 having reeling rolls 25 for loosening the blank on the 40 mandrel to facilitate stripping. The respective rolls 25 are mounted upon cross shafts 26 driven by a motor 27 through gearing 28 and driving connections 29. A guide 30 and a roller conveyor 31 assist in properly guiding and advancing 45 the mandrel and blank.

The mandrel having the reeled or loosened blank thereon passes toward the right on a roller conveyor 32 to a position at which it is lifted by the fingers 33 and moved laterally over the 50 rails 34 to a roller conveyor 35 cooperating with a stripper 36, similarly to the embodiment of Figure 1. The stripped blank is lifted from the conveyor 35 by fingers 37 and transferred on rails 38 to a roller conveyor 39 55 which feeds it to a saw 40, also similarly to the embodiment of Figure 1. The stripped and sawed blank passes to the left upon a roller conveyor 41.

At this point the blank may be reheated in a reheating furnace 42 or, if at a proper temperature, may by-pass the heating furnace by any suitable conveying mechanism (not shown), and is fed toward the right on a roller conveyor 43. An elongating mandrel 44 is introduced into the blank and the blank with the elongating mandrel 65 therein is removed from the conveyor 43 by fingers 45 and passes laterally along rails 46 to a roller conveyor 47 from which it is moved toward the left through an elongator 48, which, together with its associated mechanism, may be substantially a counterpart of the elongator 3 of Figure 1. From the elongator 48 the blank having the mandrel 44 therein passes toward the left on a runout table 49 and the elongator mandrel is withdrawn. This may be done by an extractor 70

similar to the extractor 36. The elongator mandrel may be of substantially smaller size than the push bench mandrel, resulting in relatively heavy reduction, both in diameter and in wall thickness, and also relatively great elongation in the elongator.

The blank on the conveyor 49 may be considered to be a finished article of commerce or tube, although it is also adapted for further treatment in a reducing mill either with or without reheating, as in the case of the blank emerging on the conveyor 20 in Figure 1. The reducing mill shown in Figure 3 may form a part of the mill of Figures 2A and 2B, receiving the blank from the conveyor 49.

Thus relatively small thin walled tubing may be manufactured at remarkably low cost and at high speed. From a comparatively short blank of relatively great wall thickness emerging from the push bench a tube many times as long and of much less diameter and wall thickness may be produced. The economies of the push bench are obtained, yet products heretofore ordinarily manufactured on a piercing mill are made.

25 While I have shown and described certain present preferred embodiments of the invention, it is not to be distinctly understood that the same is not limited thereto, but may be otherwise variously embodied and practiced within the scope of the 30 following claims.

I claim:

1. A process for the manufacture of tubes, comprising thinning and longitudinally elongating a blank over a mandrel in a push bench, and thereafter simultaneously further thinning and longitudinally elongating said blank over said mandrel and loosening said blank with respect to said mandrel while maintaining the exterior of the blank substantially smooth.

40 2. A process for the manufacture of tubes, comprising thinning and elongating a blank over a mandrel in a push bench, and thereafter elongating said blank over a mandrel between cross rolls.

45 3. A process for the manufacture of tubes, comprising thinning and elongating a blank over a mandrel in a push bench, stripping the blank from said mandrel, and thereafter elongating said blank over another mandrel between cross rolls.

50 4. A process for the manufacture of tubes, comprising thinning and elongating a blank over a mandrel in a push bench, stripping the blank from said mandrel, inserting another mandrel into said blank, and elongating said blank over said second mentioned mandrel by passing the blank and mandrel between rolls.

55 5. A process for the manufacture of tubes, comprising thinning and elongating a blank over a mandrel in a push bench, stripping the blank from said mandrel, inserting into the stripped blank another mandrel of less diameter than said first mentioned mandrel, and elongating said blank over said second mentioned mandrel by passing the blank and mandrel between rolls.

60 6. A process for the manufacture of tubes, comprising thinning and elongating a blank over a mandrel in a push bench, and thereafter simultaneously spinning and elongating said blank over a mandrel.

65 7. A process for the manufacture of tubes, comprising thinning and elongating a blank over a mandrel in a push bench, removing said mandrel and blank from the push bench, thereafter further elongating said blank over a mandrel, and

thereafter reducing said blank in a reducing mill.

8. A process for the manufacture of tubes, comprising thinning and elongating a blank over a mandrel in a push bench, thereafter further elongating said blank over a mandrel between 5 cross rolls, and thereafter reducing said blank in a reducing mill.

9. A process for the manufacture of tubes, comprising thinning and elongating a blank over a mandrel in a push bench, reeling the blank to 10 loosen it from the mandrel, stripping the blank from said mandrel, inserting into the stripped blank another mandrel, thinning and elongating the blank over said second mentioned mandrel, and thereafter reducing said blank in a reducing 15 mill.

10. A process for the manufacture of tubes, comprising thinning and elongating a blank over a mandrel in a push bench, stripping the blank from said mandrel, inserting into the stripped 20 blank another mandrel of less diameter than said first mentioned mandrel, thinning and elongating the blank over said second mentioned mandrel, and thereafter reducing said blank in a 25 reducing mill.

11. A process for the manufacture of tubes, comprising thinning and elongating a blank over a mandrel in a push bench, stripping the blank from said mandrel, heating the blank, inserting 30 into the blank another mandrel, and elongating the blank over said second mentioned mandrel by passing the blank and mandrel between rolls.

12. A process for the manufacture of tubes, comprising thinning and elongating a blank over a mandrel in a push bench, stripping the blank 35 from said mandrel, inserting into the stripped blank another mandrel of less diameter than said first mentioned mandrel, thinning and elongating the blank over said second mentioned mandrel between cross rolls, and thereafter reducing said 40 blank in a reducing mill.

13. A process for the manufacture of tubes, comprising thinning and elongating a blank over a mandrel in a push bench, and thereafter thinning and elongating said blank over a mandrel 45 while rendering the same relatively loose thereon.

14. Apparatus for tube manufacture, comprising a push bench having dies and a mandrel and an elongator provided with cross rolls between which a mandrel with a blank thereon is adapted 50 to pass to further elongate the blank after a precedent thinning and elongation in the push bench.

15. Apparatus for tube manufacture, comprising a push bench having dies and a mandrel, a stripper, means for inserting another mandrel into a stripped blank after a precedent thinning and elongation in the push bench, and an elongator provided with cross rolls between which said second mentioned mandrel with the blank thereon is adapted to pass.

60 16. Apparatus for tube manufacture, comprising a push bench having dies and a mandrel, an elongator having cross rolls and a reducing mill, said push bench, elongator and reducing mill being constructed and arranged to successively operate on a blank.

17. Apparatus for tube manufacture, comprising die means for thinning and longitudinally elongating a blank over a mandrel and means for further thinning and longitudinally elongating said blank over a mandrel while rendering the same relatively loose thereon and maintaining the exterior of the blank substantially smooth.

70 18. Apparatus for tube manufacture, comprising a push bench having dies and a mandrel, a 75

reeler, a stripper, means for inserting another mandrel into a stripped blank after a precedent thinning and elongation in the push bench, and an elongator provided with cross rolls between which said second mentioned mandrel with the blank thereon is adapted to pass.

19. Apparatus for tube manufacture, comprising a push bench having dies and a mandrel, a stripper, means for supplying another mandrel

for insertion into a blank, and an elongator through which said second mentioned mandrel with the blank thereon passes.

20. Apparatus for tube manufacture, comprising a push bench having dies and a mandrel, a stripper, means for supplying another mandrel for insertion into a blank, an elongator, and a reducing mill.

CARL W. LITTLER.
